US0D1033992S

(12) **United States Design Patent** (10) **Patent No.:** **US D1,033,992 S**
(45) **Date of Patent:** **** Jul. 9, 2024**

(54) **INFLATABLE CUSHION**

(71) Applicant: **Pan Hu**, Qichun (CN)

(72) Inventor: **Pan Hu**, Qichun (CN)

(**) Term: **15 Years**

(21) Appl. No.: **29/841,335**

(22) Filed: **Jun. 6, 2022**

(51) LOC (14) Cl. **06-09**

(52) U.S. Cl.

USPC **D6/604**

(58) **Field of Classification Search**

USPC ..... D6/595-601, 604, 606, 610; D21/797, D21/803-804, 808-809, 839, 203, 416; D24/183-184; 5/413 R, 413 AM, 417, 5/419
